DESIGN FOR A BED LAMP

Louis Ludwig, Brooklyn, N. Y.

Application August 13, 1938, Serial No. 79,310

Term of patent 14 years

To all whom it may concern:

Be it known that I, Louis Ludwig, a citizen of the United States and a resident of Brooklyn, county of Kings, State of New York, have invented a new, original, and ornamental Design for Bed Lamp, of which the following is a specification, reference being had to the accompanying drawing, forming part thereof, and in which,

I claim:

The ornamental design for a bed lamp, as shown.

LOUIS LUDWIG.
